ADJUSTABLE HANGER FOR ELECTRIC
OUTLET BOXES

Charles Hoffman, Salisbury, Md.

Application December 12, 1952, Serial No. 325,617

3 Claims. (Cl. 248—57)

1

This invention relates to supports for electrical outlet boxes, and more particularly to an improved adjustable support adapted to be employed for supporting an outlet box from spaced joists.

A main object of the invention is to provide a novel and improved adjustable support for an electrical outlet box particularly suitable for use in supporting an outlet box between spaced joists, as for example, in buildings where steel ceiling joists are placed more than two feet apart and where the ceiling is hung on the bottom of the joist or suspended below the joist.

A further object of the invention is to provide an improved adjustable support for an electrical outlet box particularly suitable for use between steel ceiling joists, the outlet box being adjustably supported in a desired position, the supporting means being arranged to provide any desired height of the outlet box over a relatively wide range of adjustments, the supporting device being simple in construction, being easy to install and involving inexpensive components.

Further objects and advantages of the invention will become apparent from the following description and claims, and from the accompanying drawing, wherein:

Figure 1 is a side elevational view, partly in vertical cross section, showing an electrical outlet box supported by improved adjustable supporting means constructed in accordance with the present invention.

Figure 2 is a cross sectional view taken on the line 2—2 of Figure 1.

Figure 3 is an enlarged horizontal cross sectional view taken on the line 3—3 of Figure 2.

Figure 4 is an enlarged horizontal cross sectional view taken on the line 4—4 of Figure 2.

Referring to the drawings, 11, 11 designate respective portions of ceiling joists, such as hangers connected to respective spaced ceiling joists, or other spaced structural elements from which it is desired to support an outlet box, shown at 12. Designated at 13 is a horizontal tubular bar which is engaged by and supported by the members 11, 11, as, for example, by the provision of respective apertures in the members 11, 11 through which the end portions of the tubular bar 13 extend. Designated at 14 is a vertical sleeve member formed with diametrically opposed openings through which the tubular bar member 13 extends, the openings being shown at 15, 15 in Figure 1. Slidably engaged through the sleeve member 14 on opposite sides of the tubular bar member 13 are respective spaced par-

2

allel arms 16 and 17 said arms being integrally connected at their lower ends by the sleeve portion 18, the arms 16 and 17 being arcuate in cross section and being arranged coaxially with the sleeve portion 18. Each of the arms 16 and 17 is formed with the spaced apertures 19, the apertures 19 of the arm 16 being staggered relative to the apertures of the arm 17, and said apertures being spaced uniformly along the respective arms. Designated at 20 is a set screw which is threadedly engaged through the wall of the sleeve member 14 and which is engageable through a selected aperture 19 in one of the arms, as shown in Figure 2, the set screw 20 extending over the horizontal tubular bar 13 transversely thereto and being clampingly engageable with the inside surface of the opposite arm 17. For example, the screw 20 is engaged through a selected aperture 19 in the arm 16 and clampingly engages the inside surface of the opposing arm 17. Thus, the sleeve portion 18 is suspended in a desired adjusted position relative to the horizontal tubular arm 13.

The sleeve member 18 is formed with the outwardly projecting lug elements 21, 21 which are diametrically opposed, as shown in Figure 2. The sleeve member 18 is engaged through the central opening in the major wall of the outlet box 12, and disposed on the lower end of the sleeve member 18 is the stud member 22, said stud member having the flaring skirt portion 23 which is engageable against the inside surface of the major wall 24 of the outlet box adjacent the central aperture therein. Extending axially through the stud member 22 is the fastening screw 25 which is threadedly engaged in a transverse bar member 26. The bar member 26 extends through diametrically opposed apertures 27, 27 formed in the sleeve member 18 above the outwardly flared lugs 21, 21, the respective outer ends of the bar member 26 being notched at 28 and the resultant segments being spread outwardly, as shown at 29, 29 to secure the bar member in the sleeve 18.

As shown in Figure 3, the respective lugs 21, 21 may comprise opposed downwardly flared arcuate ribs extending for substantial distances around the circumference of the sleeve member 18, whereby the outlet box is rigidly locked to the sleeve member when the screw 25 is tightened.

It will be readily apparent that the outlet box 12 may be readily secured to the sleeve member 18, as above described, by inserting the end 55 of the sleeve member 18 into the central aper-

ture in the major wall 24 of the outlet box, then engaging the stud 22 over the lower end of the sleeve member, and then engaging the screw 25 through the central aperture in the stud member 22 and into the threaded opening in the central portion of the transverse bar member 26. By tightening the screw, the outlet box 12 is locked to the sleeve member 18. The sleeve member 14 is disposed on the horizontal tubular bar 13, and the bar 13 is engaged with the supporting members 11, 11. The arms 16 and 17 are then inserted through the sleeve member on opposite sides of the tubular bar 13, and the screw 20 is then engaged through a selected aperture 19 in one of the arms and tightened to engage the inside surface of the opposite arm, whereby the supporting structure is completely installed and the outlet box is ready for receiving the electrical elements to be contained therein.

While a specific embodiment of an improved hanger device for an electrical outlet box has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. In combination, a horizontal support member adapted to be engaged between a pair of joists, a sleeve member formed with diametrically opposed openings receiving said support member, a hanger bar having spaced parallel apertured arms and a sleeve portion connecting said arms, said arms being slidably engageable through said first sleeve member on opposite sides of said support member, a fastening member extending over the horizontal support member secured in said first sleeve member and extending through a selected aperture in one of said arms, an outlet box formed with an aperture receiving said last-named sleeve portion, a transverse bar element extending through said last-named sleeve portion above the outlet box, means on said last-named sleeve portion limiting upward movement of the outlet box, a stud member engaged on the bottom end of said last-named sleeve portion and engaging the outlet box adjacent the aperture therein, and a fastener extending axially through said stud member and lockingly engaged with said transverse bar element.

2. In combination, a horizontal support member adapted to be engaged between a pair of joists, a sleeve member formed with diametrically opposed openings receiving said support member, a hanger bar having spaced parallel apertured arms and a sleeve portion connecting said arms, said arms being slidably engageable through said first sleeve member on opposite sides of said support member, a fastening screw extending through the wall of said first sleeve member and extending through a selected aperture in one of said arms over said support member, an outlet box formed with an aperture receiving said last-named sleeve portion, a transverse bar element extending through said last-named sleeve portion above the outlet box, means on said last-named sleeve portion limiting upward movement of the outlet box, a stud member engaged on the bottom end of said last-named sleeve portion and engaging the outlet box adjacent the aperture therein, and a fastening screw extending axially through said stud member and threadedly engaged with said transverse bar element.

3. In combination, a horizontal support member adapted to be engaged between a pair of joists, a sleeve member formed with diametrically opposed openings receiving said support member, a hanger bar having spaced parallel apertured arms and a sleeve portion connecting the lower ends of said arms, said arms being slidably engageable through said first sleeve member on opposite sides of and transverse to said support member, a fastening screw extending through the wall of said first sleeve member and extending through a selected aperture in one of said arms over said support member and clampingly engaged against the other arm, an outlet box formed with an aperture receiving said last-named sleeve portion, a transverse bar element extending through said last-named sleeve portion above the outlet box, opposed outwardly extending lugs on said last-named sleeve portion limiting upward movement of the outlet box, a stud member engaged on the bottom end of said last-named sleeve portion and engaging the outlet box adjacent the aperture therein, and a fastening screw extending axially through said stud member and threadedly engaged with said transverse bar element.
